UNITED STATES PATENT OFFICE

2,502,675

CLEANABLE TYPE HEAT EXCHANGER

Clyde S. Simpelaar, Racine, Wis., assignor to
Modine Manufacturing Company, Racine, Wis.,
a corporation of Wisconsin

Application December 23, 1946, Serial No. 717,987

2 Claims. (Cl. 257—239)

1

The invention relates generally to heat exchangers, and more particularly to a cleanable type of heat exchanger.

The utilization of heat exchangers in certain applications, particularly for use in chemical and food industries, requires that such equipment be so constructed that the same may be readily cleaned.

In the past, heat exchangers utilizing a plurality of heat exchange tubes or a tube bundle, while providing easy accessibility for cleaning the tubes, have been so constructed that adequate cleaning of the outside tube surfaces could not be obtained. This condition resulted from the necessity of closely spacing tubes to secure adequate heat transfer in reasonable bulk, maintaining a gasketed seal at the free end of the tube bundle, as well as the necessity of having access to both ends of the exchanger.

It will be apparent that as the conventional tube bundle type of exchanger with a floating end requires considerable precision machining of the shell and piston-like head to secure a satisfactory seal, the cost of construction is necessarily greater, and the overall size is increased, as such construction requires a shell having an internal diameter substantially larger than the overall diameter of the tube bundle.

The present invention has, among its objects, the production of a heat exchanger which does not require accessibility at both ends for cleaning, but at the same time provides ready accessibility of both ends of the tubes in which both passes or sides of the exchanger are mechanically cleanable.

Another object of the invention is the production of such a heat exchanger having a minimum number of joints between the fluids passed through the same in heat exchange relation, and embodying a simple casing and tube bundle structure which does not require any machine fits at the floating end, whereby the present invention may be utilized for heat exchange of fluids under high pressure.

A further invention is the production of such an exchanger having a finned tube bundle structure which may be easily removed from its casing, and in which the internal diameter of the latter is relatively little greater than the diameter of the tube bundle.

A further object of the invention is the production of a heat exchanger having high efficiency in which the baffles incorporated therein are also utilized as heat transfer surfaces, and the space normally occupied by a floating piston tube mem-

2

ber in the conventional exchangers utilized for additional heat transfer.

Many other objects and advantages of the construction herein shown and described will be obvious to those skilled in the art from the disclosure herein given.

To this end my invention consists in the novel construction, arrangement and combination of parts herein shown and described, and more particularly pointed out in the appended claims.

In the drawings, wherein like reference characters indicate like or corresponding parts:

Fig. 1 is a longitudinal sectional view of a heat exchanger embodying the present invention, taken approximately on the line 1—1 of Fig. 2;

Fig. 2 is a sectional view taken approximately on the line 2—2 of Fig. 1, and

Fig. 3 is a sectional view taken approximately on the line 3—3 of Fig. 2.

The present invention contemplates the use of tubes bent or otherwise formed into a more or less U-shape, whereby both ends of each tube may be secured to a single tube sheet, the main portions of the tubes being positioned substantially at one side of the tube sheet with the tubes opening on the other side of the sheet. Provision is made for circulating a fluid through the tubes and circulating another fluid across the exterior surfaces of the tubes, to which may be secured a plurality of heat transfer fins, the tubes being so constructed that the only joints existing between the two fluids being circulated are the connections of the tube ends with the single tube sheet, and as such tubes are soldered, brazed or otherwise bonded to the tube sheet, all gasketed joints between the circulating fluids are eliminated.

Referring to the drawings, 1 indicates generally a casing, illustrated in the present instance as being cylindrical in cross-section, having an end wall 2, permanently secured thereto by welding or the like or, if desired, made integrally with the sides of the casing. The opposite end of the casing 1 is provided with an outwardly extending peripheral flange 3, seated upon a tube sheet 4, a suitable gasket 5 being interposed therebetween. Positioned at the opposite side of the tube sheet 4 is a tubular cover member, indicated generally by the numeral 6, closed at its outer end by an end wall 7, permanently secured thereto or integrally formed therewith, the opposite or inner end of the cover 6 being provided with an outwardly extending peripheral flange 8 corresponding to the flange 3 of the casing, a gasket member 5' being interposed between the flange 8 and the

adjoining portion of the tube sheet 4. The casing 1, cover 6 and tube sheet 4 are secured together by any suitable means, such as the bolts 9 passing through the flange 8, tube sheet 4 and flange 8 and the cooperating nuts 11. Positioned within the casing 1 are a plurality of tubes 12 and 13, which are provided with reverse bends 14 and 15 respectively, whereby the ends of the tubes are brought back and secured to the tube sheet 4, the latter being provided with apertures 16 of a size to receive the tubes which are secured to the sheet by soldering, brazing or other suitable means, all of the tubes opening on the side of the tube sheet adjacent the cover 6.

It will be noted that the tubes are arranged in two horizontal rows, with the bends of the respective tubes lying in parallel planes, and the curved portions 14 of the tubes 12 extending beyond the curved portions 15 of the tubes 13, the latter tubes being positioned between the two legs of the respective tubes 12.

Secured to the tubes 12 and 13 are a plurality of heat transfer fins 17, the side edges 18 of which are shaped to closely fit the adjacent surface of the casing 1, while the edges 19 and 21 thereof are spaced from the adjacent surface of the casing 1 to provide fluid passages above and below the tubes. Also secured to the tubes 12 and 13, at spaced intervals, are a plurality of baffle members 22, which in the present instance are shown as constructed from a slightly heavier material than the fins 17, and are extended to closely fit the casing 1, and block the passage above or the passage below the tubes, the baffle members 22 being positioned in the present instance to alternately block such passageways, thereby providing a circuitous fluid path across the tubes 12 and 13 and fins 17. It will be apparent that the number of baffle members 22 may be varied to provide any desired number of fluid passes across the tube bundle.

The casing 1 is provided with suitable pipe flanges 23 and 24 for making connections with fluid supply pipes 25 and 26, either of the pipes 25 and 26 forming the fluid inlet or outlet. For the purpose of illustration, the fluid flow through the casing 1 is indicated in Fig. 1 by arrows with the pipe 25 being the inlet and the pipe 26 the outlet, fluid in such case entering the casing from the pipe 25, passing across the looped ends 14 and 15 of the tubes around the baffle 22, adjacent the closed end of the casing, but across the tubes and around the top of the second baffle 22, and so on until it passes from the casing through the pipe 26. It will be noted that fluid entering the casing from the pipe 25 passes over the looped ends 14 and 15, thereby providing heat transfer in this space, which would normally be occupied in the conventional exchanger by a floating piston type head, providing substantially no heat transfer.

Each of the tubes 12 and 13 are provided with one long leg 27 and one short leg 28, the latter in the present instance terminating substantially flush with the face of the tube sheet 4 adjacent the cover 6, as clearly illustrated in Figs. 1 and 3, while the legs 27 project outwardly into the cover 6. Positioned in the cover 6 is a baffle member 29, having apertures 31 therein, through which the ends of the legs 27 extend. The baffle member 29 may be held in position by any suitable means, as, for example, an internally extending flange 32, carried by the cover 6, and a plurality of sleeves 33 encircling the legs 27 and seated at their respective ends on the tube sheet 4 and baffle member 29. The latter is preferably held

in position by such interlocking between the respective parts, rather than by any bonding means, to facilitate dis-assembly and cleaning of the tubes, as will hereinafter be described.

It will be noted that the baffle member 29 divides the interior of the cover 6 into two chambers 34 and 35 respectively, the chamber 34 communicating with the open ends of the relatively long legs 27 of the tubes, while the chamber 35 communicates with the open ends of the relatively short legs 28 of the tubes. The cover 6 is provided with two pipe flanges 36 and 37 for connection with suitable pipes 38 and 39, forming an inlet and outlet for the second fluid being circulated through the exchanger. Either of the pipes may be utilized as the inlet or outlet. For example, assuming the pipe 38 to be the inlet, fluid will flow through the tubes in the directions indicated by arrows in Fig. 1, fluid entering into the chamber 34, passing into the legs 27 of the tubes and through the same, being exhausted into the chamber 35 and out through the pipe 39.

It will be apparent that as the same fluid flows on both sides of the baffle 29, it is not necessary to provide a sealed or gasketed joint between the same and the cover 6 or tube legs 27, a close fit within production tolerances being satisfactory, as any fluid by-passed around the baffle from one chamber to another will be negligible in amount. The same is also true of the baffles 22.

Extending parallel with the legs of the tubes 12 and 13 in the construction illustrated, are a number of sections of tubing 41 which, as illustrated in Fig. 3, do not extend completely through the tube sheet 4, and if desired may be closed at their ends adjacent the looped portions 14 and 15 of the tubes 12 and 13, respectively. The tubes 41 are utilized merely to preserve a substantially geometrical tube pattern and resultant flow pattern across the tubes and fin surfaces, and also provide to some extent additional heat transfer surface.

To clean the exchanger it is necessary merely to remove the bolts 9 and the cover 6, disconnecting the pipes 38 and 39, if necessary, after which the tube sheet 4 and associated tubes and fins may be withdrawn from the casing. The baffle member 29 is removed from the legs 27, thereby exposing the open ends of the shorter legs 28 of the tubes, whereby suitable cleaning apparatus may be run through the tubes, the radius or curvature of the looped ends 14 and 17 being of sufficient size to permit the passage of ordinary tube cleaning apparatus. Likewise, as indicated in Fig. 2 of the drawing, a brush B or other device may be readily passed between the various outer tube and fin surfaces to clean the latter, and, if desired, the entire tube structure may be readily dipped or soaked in cleaning or solvent solutions, or further cleaned by the use of steam. Obviously, cleaning of the casing 1 and cover 6, as well as the baffle member 29 and sleeves 33, may be readily accomplished by the usual methods. After cleaning, the tube bundle is reinserted in the casing 1 and sleeves 33 applied to the legs 27 of the tubes, baffle 29 installed, and the cover 6 and bolts re-placed.

It will be noted from the above description that I have provided a heat exchanger which is readily cleanable, and in which the number of joints between the two fluids being circulated, as a result of the U-shape construction, is reduced approximately to one-third those in past devices.

It will also be noted that the present construction provides a very efficient device which may

be relatively inexpensively manufactured by the usual production methods with a minimum amount of machining, and with a saving in bulk for the heat transfer efficiency achieved.

Having thus described my invention, it is obvious that various immaterial modifications may be made in the same without departing from the spirit of my invention; hence, I do not wish to be understood as limiting myself to the exact form, construction, arrangement and combination of parts herein shown and described, or uses mentioned.

What I claim as new and desire to secure by Letters Patent is:

1. In a cleanable type heat exchanger, the combination of a tube sheet, a plurality of substantially U-shaped tubes positioned substantially at one side of said sheet and having their legs secured thereto and opening on the other side of said sheet, the respective tubes being bent on substantially equal radii, the distance between adjacent legs of adjoining tubes being less than the distance between the legs of each respective tube, one leg of each tube being longer than the other leg thereof, said tubes having a plurality of substantially flat parallel transverse fins secured thereto and carried thereby, a hollow casing of a size to removably receive the finned tubes, with the open end seated upon said tube sheet, gasket means interposed between the adjoining portions of said sheet and casing, the latter having a pair of fluid inlet and outlet openings therein, certain of said fins extending beyond the others to form baffle means for directing fluid across the tubes and fins as it flows from one opening to the other, a hollow cover member having its open end seated upon the other side of said tube sheet, gasket means interposed between the adjoining portions of said sheet and cover, said cover member having an inlet port and outlet port therein, a baffle member removably positioned in said cover member between said inlet and outlet ports to separate the same, the longer legs of said U-shaped tubes extending through said baffle member and communicating with one of said ports, and the shorter legs of said tubes terminating behind said baffle member and communicating with the other port in said cover, and means for securing said casing, tube sheet and cover in assembled relation.

2. In a cleanable type heat exchanger, the combination of a tube sheet, a plurality of substantially U-shaped tubes positioned substantially at one side of said sheet with their legs secured thereto and opening on the other side of said sheet, the respective tubes being bent on substantially equal radii, the distance between adjacent legs of adjoining tubes being less than the distance between the legs of each respective tube,

one leg of each tube being longer than the other leg thereof, a plurality of straight tubes secured at one end to said tube sheet cooperable with and so arranged with respect to said U-shaped tubes as to provide a substantially uniform distance between and a regular flow pattern across said tubes, said tubes having a plurality of substantially flat parallel transverse fins secured thereto and carried thereby, a hollow casing, open at one end, of a size to removably receive the finned tubes, and having a peripheral flange at its open end operatively seated upon said tube sheet, gasket means interposed between the adjoining portions of said sheet and said flange, said casing having a pair of fluid inlet and outlet openings therein, one opening being positioned adjacent the inner curved ends of said tubes and the other opening positioned adjacent the open end of said casing, portions of certain of said fins extending beyond the others to form baffle means for directing fluid across the tubes and fins as it flows from one opening to the other, a hollow cover member having a peripheral flange at its open end operatively seated upon the other side of said tube sheet, gasket means interposed between the adjoining portions of said sheet and the cover flange, said cover member having an inlet port and an outlet port therein, a baffle member removably positioned in said cover member between said last mentioned ports to separate the same, the longer legs of said U-shaped tubes extending through said baffle member and communicating with their adjacent port and the shorter legs of said tubes terminating behind said baffle member and communicating with their adjacent port, and means, passing through the respective flanges and the portion of the tube sheet interposed therebetween, for securing the same in assembled relation.
